UNITED STATES PATENT OFFICE.

HOWARD SPENCER LEVY, OF PHILADELPHIA, PENNSYLVANIA.

ETCHING-MACHINE.

1,042,699.

Specification of Letters Patent. Patented Oct. 29, 1912.

Application filed September 20, 1911. Serial No. 650,407.

To all whom it may concern:

Be it known that I, HOWARD SPENCER LEVY, citizen of the United States of America, residing at Philadelphia, county of 5 Philadelphia, Pennsylvania, have invented certain new and useful Improvements in Etching-Machines, of which the following is a specification.

My invention relates to etching machines 10 of that type wherein the objects to be etched, such as printing plates and the like, are adapted to have the etching acid or liquid erodent projected against the exposed face thereof.

One of the principal objects of my invention 15 is to provide means for projecting the erodent against the face of the plate so that the etching will be deep and clear, and all undercutting avoided.

A further object is to provide means for 20 permitting the fumes of the etching acid employed to readily escape out of the machine.

A further object is to provide means 25 whereby different sized plates may be etched in the same apparatus without interchange or adjustment of parts.

Other objects and advantages of the invention and its detail structure will be fully 30 disclosed in the following specification reference being had to the accompanying drawing, wherein—

Figure 1 is a side elevational view of my apparatus, one of the lateral walls being 35 removed to show the interior construction; Fig. 2 is a vertical sectional view taken on the line 2—2 of Fig. 1 and looking in the direction of the arrows; and Fig. 3 is a detail hereinafter referred to.

In carrying my invention into practice 40 I provide a suitable acid proof receptacle wherein the etching action takes place, and the preferred form of this receptacle is best shown in Fig. 1 of the drawing. The receptacle comprises the base 10; rear wall 11; top 12 having the overhanging portion 12^a; the front wall consisting of the fixed section 13 and the pivoted or hinged section 13^a 45 which is hinged to 13 at 13^b; and the side walls 14 (only one of which is shown in Fig. 1). Projecting into the receptacle from

the wall 11 are several brackets or shelves 15, varying in width and arranged at different distances from the base 10. These shelves are adapted to support printing 55 plates 16 during the etching operation. By the provision of a series of shelves 15 constructed in the manner shown, plates of varying sizes may be etched in the same machine without modification of the latter. 60 The plate 16, shown in Fig. 1 as resting on the lowermost of the series of shelves 15, is intended to represent the largest plate which could be effectively etched in an apparatus of this kind. To permit of the 65 plates 16 being inserted in, and removed from, the machine, the upper horizontal section of top wall 12 is mounted on a hinge 12^b, whereby this top wall section may be moved to open or close the machine, as re- 70 quired.

In one of the side walls 14 is provided a series of orifices 17 in the uppermost one of which a plug or pin 18 is shown as being inserted. The hinged section 13^a of the 75 front wall is adapted to rest upon the plug 18, and as the latter may be inserted into any of the orifices 17 the space between the top edge of the section 13^a and the underside of the top 12 of the receptacle may be ad- 80 justed. This space, which in the drawing is designated by the arrow 19, forms one of the passages through which the fumes from the etching acid pass out of the receptacle. The section 13^a has formed thereon a projec- 85 tion or plate 13^c which with the overhang 12^a of the top of the receptacle forms the final emission passage 20 through which the fumes from the etching acid pass. The inner face of the hinged section 13^a of the 90 wall acts to deflect toward the plate any spray which is thrown in a substantially vertical direction by the sprayers, herein- 95 after more fully described. If the plate to be etched is of maximum size, as that shown in Fig. 1, the section 13^a rests on the plug 18 inserted in the uppermost orifice 17, while if the plate is smaller the section 13^a is cor- 100 respondingly lowered. The overhang 12^a and the projection 13^c act as baffles for the acid fumes which issue from the machine through the passage 19—20.

To properly etch the printing plate or other object to be treated it is eminently desirable that the etching fluid be projected, preferably in spray form, and as nearly uniformly as possible, over the whole exposed face of the plate. To accomplish this result I employ a plurality of what I term mechanical sprayers the function of which is to dip into the erodent and project the same, uniformly, and in spray form, over the face of the plate. The etching acid or erodent 21 is filled into the receptacle until it stands therein at a predetermined level and the mechanical sprayers revolve in the liquid and project the same as spray against the exposed face of the plate 16. The receptacle may be drained of its liquid contents by the cock 21^a. I preferably employ several series of sprayers of different diameters so that as these sprayers revolve they will project the liquid to different heights against the plate 16 causing simultaneous impact of the spray against substantially the entire exposed face. Each sprayer is formed of a wheel or disk 22 having at each lateral face radial inclined slots 22^a of suitable pitch and width, extending to a point short of the center of the disk, that part of the disk containing the slots being preferably thicker than the disk at its central portion. In practice, all the disks 22 are provided with slots 22^a, although in Fig. 2 of the drawing only two of the disks are shown as having these slots. A series of such disks 22 is mounted on a shaft 23, one end thereof projecting beyond one wall 14 and carrying a belt pulley 24, there being near the other end of the shaft a bearing block 25 having lateral lugs 26 through which the bolts 27 pass to enter the holes 28 formed in opposed series in the wall 14. By the arrangement just described the shafts 23 with their disks 22 may be raised or lowered and held in adjusted position. The wall 14 is provided with the elongated slot 29 in which the block 25 slides, and to prevent the emission of liquid through this slot each of the shafts 23 carries near the end adjacent the slot a dished plate 30 revolvable with the shaft and acting as a liquid deflector or buffer. In the drawing I have shown three series of disks 22 mounted on as many shafts arranged behind each other horizontally. The disks are of progressively increasing diameter the object in view being to have each series of disks project liquid up to a certain horizontal level on the plate, the highest level to which one series of disks projects the liquid corresponding substantially to the lowest level to which the next series of disks projects the liquid, the result of this arrangement being that there is a continuous uniform spray of liquid over the whole exposed face of the plate. In a preferred form of the invention each series of

disks is arranged on a separate shaft and each shaft is provided with its own belt pulley so that each shaft may be separately power driven, whereby I am enabled to drive all the shafts with their disks in the same direction, or I may if desired drive the shafts in directions opposite to each other. The opposite drive of the shafts may be desirable in a case where for example it is desired to drive the smaller series of disks in a direction opposite that in which the next larger series is driven so that the liquid will be positively projected upwardly by the smaller disks and tend to counteract the downward flow of liquid projected by the next larger series. The preferred arrangement of disks is that shown in Figs. 1 and 2 wherein the disks of the foremost row are the smallest in diameter, the disks of the next series being larger and the disks of the rearmost series being the largest. I also prefer to so arrange the disks that those on the intermediate shaft project between adjacent disks of the first shaft and those on the rearmost shaft project between those on the intermediate shaft.

From the foregoing description, taken in connection with the accompanying drawing, it will be noted that I have provided simple and effective means for accomplishing the following results:—(1) supporting different sized plates in the machine without modification of any of its parts; (2) projecting the etching fluid in the form of spray uniformly to cover the whole exposed face of the plate both horizontally and vertically; (3) leading the fumes, in a greater or less volume, out of the machine; (4) adjusting the mechanical sprayers vertically in the receptacle so that the sprayers dip into the liquid precisely the extent required to effectively project the liquid against the plate; and (5) preventing liquid from flowing out of the receptacle at the points where the shafts which carry the disks bear in the side walls of the receptacle.

Having thus described my invention what I claim as new and desire to secure by Letters Patent is:—

1. In an etching machine, the combination with a receptacle to contain the etching fluid, of a plurality of means in said receptacle differing in size from each other for projecting the etching fluid to different heights against the object to be etched.

2. In an etching machine, the combination with a receptacle to contain the etching fluid, of a plurality of revolvable means in said receptacle differing in size from each other for projecting the etching fluid to different heights against the object to be etched.

3. In an etching machine, the combination with a receptacle to contain the etching fluid, of a plurality of different sized me-

- chanical sprayers in said receptacle for projecting the etching fluid to different heights against the object to be etched.
4. In an etching machine, the combination with a receptacle to contain the etching fluid, of different sized revoluble disks in said receptacle for projecting the etching fluid to different heights against the object to be etched.
5. In an etching machine, the combination with a receptacle to contain the etching fluid, of a plurality of series of disks in said receptacle, the disks of one series being of different diameter from the disks of the other series, said disks being adapted to project the etching fluid to different heights against the object to be etched.
- 10 6. In an etching machine, the combination with a receptacle to contain the etching fluid, of a plurality of series of disks in said receptacle arranged in a horizontal row, the diameter of said disks progressively increasing from that of the foremost series to that of the rearmost series, said disks being adapted to project the etching fluid to different heights against the object to be etched.
- 15 7. In an etching machine, the combination with a receptacle to contain the etching fluid, of a plurality of shafts vertically adjustable in said receptacle, and means carried by said shafts for simultaneously projecting the etching fluid to different heights against the object to be etched.
- 20 8. In an etching machine, the combination with a receptacle to contain the etching fluid, of a plurality of shafts vertically adjustable in said receptacle, and a series of disks on each shaft for projecting the etching fluid against the object to be etched.
- 25 9. In an etching machine, the combination with a receptacle to contain the etching fluid, of a plurality of shafts bearing in said receptacle, and a series of disks on each shaft, the diameter of the disks on one shaft differing from that of the disks on the other shafts.
- 30 10. In an etching machine, the combination with a receptacle to contain the etching fluid, of a plurality of shafts vertically adjustable in said receptacle and arranged in a horizontal row, and a series of disks on each shaft, the diameter of said disks progressively increasing from that of the foremost series of disks to that of the rearmost series.
- 35 11. In an etching machine, the combination with a receptacle to contain the etching fluid, of a mechanical sprayer in said receptacle, said mechanical sprayer including a disk having a plane peripheral surface and lateral slots cut in the material of said disk.
- 40 12. In an etching machine the combination with a receptacle to contain the etching fluid, of a mechanical sprayer in said
- receptacle, said mechanical sprayer including a disk having a plane peripheral surface and radial slots on each of its lateral faces.
- 45 13. In an etching machine, the combination with a receptacle to contain the etching fluid, of a mechanical sprayer in said receptacle, said mechanical sprayer including a disk having a plane peripheral surface and inclined radial slots on each of its lateral faces.
- 50 14. In an etching machine, the combination with a receptacle to contain the etching fluid, of a mechanical sprayer in said receptacle, said mechanical sprayer including a disk thicker at its periphery than at its central portion and having a series of inclined radial slots in each of its lateral faces at the thickened portion of said disk.
- 55 15. In an etching machine the combination with an etching-fluid receiving-receptacle having one wall thereof angularly adjustable in relation to the top of the receptacle, and means in said receptacle for projecting the fluid therein to different heights against the object to be etched.
- 60 16. In an etching machine, the combination with an etching-fluid receiving-receptacle having one wall thereof angularly adjustable in relation to the top of the receptacle, of means for retaining said wall in adjusted position, and means in the receptacle for projecting the fluid therein to different heights against the object to be etched.
- 65 17. In an etching machine the combination of an etching-fluid receiving-receptacle having an overhanging top, a wall of said receptacle adjustable in relation to the top of the receptacle, a plate on said adjustable wall projecting toward the overhang of the top, and means in the receptacle for projecting the liquid therein to different heights against the object to be etched.
- 70 18. In an etching machine the combination of an etching-fluid receiving-receptacle having one wall thereof hinged and angularly adjustable in relation to the top of the receptacle, means whereby said wall may be held in its adjusted angular position, and means in the receptacle for projecting the fluid therein to different heights against the object to be etched.
- 75 19. In an etching machine, the combination with a receptacle to contain the etching fluid, of a plurality of means varying in width for vertically supporting different sized objects to be etched in the receptacle, and means for projecting the etching fluid against said object.
- 80 20. In an etching machine, the combination with a receptacle to contain the etching fluid, of means varying in width for vertically supporting different sized objects to

be etched in the receptacle, and means in the receptacle for projecting the etching fluid against said object to a height corresponding to that at which the object stands in the receptacle. 20

21. In an etching machine, the combination with a receptacle to contain the etching fluid, of a plurality of brackets of different width extending into the receptacle 10 from one wall thereof and adapted to vertically support the objects to be etched, and means for projecting the etching fluid against said objects. 25

22. In an etching machine, the combination with a receptacle to contain the etching fluid, of a plurality of brackets of different width extending into the receptacle from one wall thereof and adapted to vertically support different sized objects to be 15

etched, and means for projecting the etching fluid against said objects to a height corresponding to that at which the object stands in the receptacle. 30

23. In an etching machine, the combination with a receptacle to contain the etching fluid, of a plurality of shafts projecting through a slot in a lateral wall of the receptacle, a fluid deflector on each shaft adjacent the slot, mechanical sprayers carried by said shafts, and means in the receptacle 35 for supporting the objects to be etched.

In testimony whereof I have affixed my signature in presence of two witnesses.

HOWARD SPENCER LEVY.
